UNITED STATES PATENT OFFICE.

JULIUS ERHARDT, OF FRIEDRICHSHAFEN-ON-THE-BODENSEE, GERMANY, ASSIGNOR
TO LUFTSCHIFFBAU ZEPPELIN GESELLSCHAFT MIT BESCHRÄNKTER HAFTUNG,
OF FRIEDRICHSHAFEN-ON-THE-BODENSEE, GERMANY.

AIRSHIP.

Application filed August 19, 1922. Serial No. 582,912.

To all whom it may concern:

Be it known that I, JULIUS ERHARDT, a citizen of Germany, residing at Friedrichshafen-on-the-Bodensee, Germany, have invented certain new and useful Improvements 5 in Airships, of which the following is a specification.

My invention relates to air-ships of the kind in which a gang-way is provided at 10 the bottom side of a rigid structure enclosing gas cells and is located within that structure lengthwise with respect to it. Air-ships of this kind have already been provided also with lateral or by-gang-ways lying at 15 right angles with respect to the main-gang-way, or transversely respectively. Some of these by-gang-ways are employed as passages to the cars if these are suspended laterally from the longitudinal axis of the air- 20 ship. The gas cells located at the by-gang-ways are bulged inwards by the structures forming the same. These structures although connected with the main structure or trellis work do not form material parts of 25 this latter; they are carried by the main frame work as are other members of the air-ship also.

It is important that the structures forming the by-gang-ways are of low weight and 30 permit of good connections with the main structure, and another essential requirement is that the cells contacting with said structures and being bulged inwards by them are not damaged. On the other hand, the pressure 35 which the gas-filled cells exert upon the structures in question is pretty high.

The present invention relates to by-gang-ways formed by structures consisting of 40 practically elliptically bent tubes which are of oblong shape in transverse section and have the long axis of this sectional shape lie in the plane of the bent tube. There is a plurality of such elliptically bent or bow-shaped tubes arranged parallelly to one another, i. e. in the direction from the main 45 gang-way to the one and the other side of the air-ship, and they are connected with each other and with the main structure by wires extending from the main gang-way to 50 lateral members of the main structure, i. e. to structure parts located behind the outer ends of the by-gang-ways. The tubes and the wires forming these ways determine, thus, the sectional configuration, as well as

the length of the same. The distance between the consecutive elliptical or similarly bent gang-way-forming tubes in such that the gas-cells cannot unduly slacken between them, and also the distance between the wires is chosen with consideration to that requirement, but to ensure the effect in question, 55 cords or the like may be provided parallelly to the flat tubes, the cords, etc., being carried by the wires and, if desired, or preferred connected with them. The tubes, the 60 wires and the cords, form wide-meshed nets which are in contact with the neighboring portions of the gas-cells and produce in these latter the large cavities receiving the 65 lateral gang-way structures.

Making use of tubes for the lateral gang-way structures is advantageous in two respects. Firstly the tubes have a low weight; secondly, it is easy to change their sectional shape, viz to change the position of the long 70 axis of the flat tube, so that the lower ends of the tubes may very securely and conveniently be connected with the bottom member of the by-gang-way, as is all more fully 75 described hereinafter. The bottom member of each of these gang-ways extends parallelly to the multi-angled, practically circular, circumferential members of the main structure forming the body of the air-ship.

My invention is illustrated, by way of 80 example, in the accompanying drawing, in which Fig. 1 is a diagrammatical illustration 85 of a vertical transverse section through one half of the bottom portion of an air-ship provided with by-gang-ways constructed according to this invention, the figure showing one such gangway in side-view, i. e. seen from an end of the air-ship. Fig. 2 is a transverse section through that gangway 90 in line a—a of Fig. 1, drawn on a somewhat larger scale. Fig. 3 is a perspective representation of a somewhat modified form of construction.

1 is the main gang-way which extends in known manner lengthwise through the body 95 of the air-ship and is rigidly connected with the frame-work of the same. It is, in the example shown, assumed that the air-ship has two cars, the one on the right hand side, the other on the left hand one. One of these 100 cars (4) is shown in Figs. 1 and 3, which shows also the by-gang-way leading from 105 the main-gang-way 1 to that car which is

accessible from the by-gang-way over the ladder 5.

The bottom of the by-gang-way is formed in the examples shown, of a ladder 12 (Fig. 3) that extends parallelly to the main circumferential structural members 2, of which some portions are visible in Figs. 1 and 3 above the car. The ladder 12 terminates at the longitudinal member 3 which forms part 10 of the trellis work. The ladder 5 extends from the car 4 to the end of the ladder 12.

Affixed to the structural members 2 are upright bows 6 formed by bent tubes of flat or elliptical sectional shape. The long axis 15 of the ellipsis lies in the plane of the bow 6, but the ends of the bow are so deformed that the long axis of the ellipsis lies parallelly to the bottom member 2, as illustrated in Fig. 2. This is done in order to be able to firmly 20 secure the bows to that bottom member. The size and shape of the bows 6 is such that they form a convenient passage to the ladder 5.

There are, in the example shown in Fig. 1, two bows 6. They are connected with each 25 other and with the trellis work by wires 7 which extend from the adjacent structural members of the main gang-way to the points 9 of the lateral trellis work. The wires 7 are connected with each other by cords 10, 30 located parallelly to the bows 6 and form, together with these latter and the wires, meshes for the purpose already stated in the preamble.

Fig. 3 differs from Fig. 1 merely by the 35 features that there are three bows 6, instead of two, and that the uppermost of the wires 7 extends from the point 7 to the upper longitudinal structural member of the gang-way 1.

40 The arrangement is preferably such that the by-gang-way is bordered at its outer end by the stayings or stiffenings of the trellis work.

I wish it to be understood that I do not desire to be limited to the exact details of 45 construction and configuration shown and described for obvious modifications will occur to a person skilled in the art.

I claim:

50 1. In an air-ship with trellis work construction enclosing a plurality of gas cells, and with a main gang-way extending lengthwise along the bottom of the trellis work, the combination, with said trellis work con-

struction, said gas cells, and said main gang-way, of by-gang-ways located at right angles to the main gang-way and being each composed of upright bows and of wires connecting said bows with each other and with the frame work, as set forth. 55

2. In an air-ship with trellis work construction enclosing a plurality of gas cells, and with a main gang-way extending lengthwise along the bottom of the trellis work, the combination, with said trellis work 60 construction, said gas cells, and said main gang-way, of by-gang-ways located at right angles to the main gang-way and being each composed of upright bows formed by tubes of flat sectional shape, 65 and of wires connecting said bows with each other and with the frame work, as set forth. 70

3. In an air-ship with trellis work construction enclosing a plurality of gas cells, and with a main gang-way extending lengthwise along the bottom of the trellis work, the combination with said trellis work construction, said gas cells, and said main gang-way, of by-gang-ways extending from said main gang-way in lateral direction and being each composed of a plurality of upright bows of approximately elliptical configuration and consisting of tubes of approximately oval sectional shape and of wires connecting said bows with each other and with the frame work, as set forth. 75 80

4. In an air-ship with trellis work construction enclosing a plurality of gas cells, and with a main gang-way extending lengthwise along the bottom of the trellis work, the combination with said trellis work construction, said gas cells, and said main gang-way, of by-gang-ways located at right angles to the main gang-way and being each composed of upright bows formed by tubes 85 of flat sectional shape, and of wires connecting said bows with each other and with the frame work, the structures forming the said by-gang-ways being located between gas cells and bulging them inwards and being 90 adapted to support the bulged-in portions of the cell walls, as set forth. 95 100

In testimony whereof I affix my signature.

JULIUS ERHARDT. [L. s.]
